UNITED STATES PATENT OFFICE

2,327,033

FILAMENT MOUNTING MACHINE

John Flaws, Jr., East Cleveland, Ohio, assignor
to General Electric Company, a corporation of
New York

Application November 26, 1941, Serial No. 420,474

15 Claims. (Cl. 176—3)

My invention relates to the mounting of filaments on the leads of a flash lamp, incandescent lamp, or similarly constructed electrical device. More particularly, my invention relates to apparatus for automatically presenting a filamentary wire in mounting relation to a pair of leads extending from a stem and for connecting said wire securely to the end portions of said leads in a satisfactory and ready manner.

Owing to the very small size and length of filaments used on low voltage circuits and the need of providing filament-to-lead connections of uniformly low resistance, the operation of mounting such filaments has always been difficult and has required considerable care and skill. One object of my invention is to provide apparatus which is particularly adapted to mount filaments of such small size and low strength as were heretofore impractical to mount commercially either manually or semi-automatically. Filaments of this type are desirable in incandescent lamps in that they increase the efficiency thereof and are desirable in flash lamps in that they reduce the electrical energy required to start said lamps and they also reduce the starting lag thereof.

Another object of my invention is to provide apparatus for automatically connecting a filament to leads in a manner which assures a very secure and low resistance connection. Such filament-to-lead connections are of utmost importance in flash lamps and the smaller incandescent lamps since lamps of these types must operate on low voltage electric currents and have uniform resistance.

Another object of my invention is to provide apparatus for mounting a very short filament on the leads of a lamp or the like.

Another object of my invention is to provide apparatus for testing the connections between the filament and leads by attempting to pull one from the other. The test operation is a direct indication of the strength of the filament-to-lead connections and also is a very reliable indication of the whole mounting operation as loose or low strength connections are almost the only cause of high resistance connections.

Another object of my invention is to provide apparatus for indicating and removing the lead and filament assemblies which have been defectively manufactured. This operation is controlled by the passage of electrical energy through the assembly after manufacture to ascertain whether said assembly has greater resistance than a satisfactory stem and is defective.

Still other objects and advantages of my invention will appear from the following detailed description of species thereof, and from the accompanying drawings.

5 In the drawings, Fig. 1 is a plan view of mount making apparatus comprising my invention; Fig. 2 is perspective view of one of the movable heads of said apparatus; Fig. 3 is a side elevation of lead wire grooving (or notching) and trimming apparatus at station A; Fig. 4 is a partially exploded perspective view of the essential parts of the filament mounting apparatus at station B; Fig. 4a is a plan view, on an enlarged scale, of a notched lead positioning plate forming part of the filament mounting apparatus; Figs. 5a and 5b are side elevations on a larger scale of the grooved end of a lead at two different stages in the mounting operation; Figs. 6 and 7 are side elevations at right angles to each other of the mounting apparatus at station B; Fig. 8 is a side elevation of groove closing means of the apparatus; Fig. 9 is a vertical section through the portion of the closing means located along line 9—9' in Fig. 8, the said means being shown at a different position than it is shown in said Fig. 8; Fig. 10 is a side elevation of test apparatus at station C; and Fig. 11 is a combination schematic drawing and wiring diagram of mount testing and control apparatus located at and adjacent station D.

30 The mounting operations taking place at the various stations A to D inclusive depend on the accurate placement of two spaced leads at each of said stations, an operation which is performed, 35 in this particular instance, by an endless belt type carrier 15 (Fig. 1) having heads 16 at regularly spaced intervals. The carrier 15 shown is that disclosed in detail in my Patent 1,907,532 of May 9, 1933. Each head 16 of the carrier 15 40 comprises one pair of jaws 17 and 18 (Fig. 2) for gripping a stem 19 in which the leads 20 and 21 are sealed, and a second pair of jaws 22 and 23 for gripping the exhaust tube 24. The vertically disposed shaft 25 and the sleeve 26 surrounding 45 it provide the means of holding the jaws 17—18 and 22—23 in proper relation and are in turn held in position by the bracket 27 which forms a link in the carrier 15 and which engages the central supporting and actuating means 28 thereof. The arm 29 on the upper end of the shaft 25 and the rod 30 which extends downwardly therefrom provide for the operation of the jaws 17—18 and 22—23. As disclosed in my patent hereinbefore referred to, the carrier 15 is preferably 55 one part of apparatus for assembling and form-

ing the stem 19, and the mounting apparatus, of which my present disclosure is an example, is arranged so as to perform the various mounting operations at various stations taken by the stem 19 in the course of its movement.

The first step in the mounting of the filament on the leads 20 and 21 occurs at station A, where the lower ends of the leads 20 and 21 are trimmed to length and, while still held by the trimming means, are grooved or notched. The apparatus for these operations appears in Figs. 1 and 3 and comprises a positioning finger 31 and a holding finger 32 which are located on opposite sides of the path of movement of the lower ends of the leads 20 and 21 and which are carried in against said leads 20 and 21 by the closing movement of the jaws 33 and 34 on which they are mounted. The V-shaped notches in the end of the finger 31 gather up and position misplaced leads 20 and 21 before the end of the finger 32 comes in contact therewith, whereupon said leads 20 and 21 are pressed against the block 35, mounted below finger 31 on jaw 33, by said finger 32. The finger 32 slides within the jaw 34 and compresses the spring 36 located between its end and the plate 37 on jaw 34 as said jaw 34 closes.

The jaws 33 and 34 are pivoted on the pin 38 carried by the standard 39 and are closed by means causing the upward movement of the slide 40 which advances the wedge shaped end 41 thereof into position between the rollers 42 on the lower ends of said jaws 33 and 34 which means is connected to said slide 40 through the rod 43. The means of actuating the rod 43 is preferably cam controlled means coupled to the common drive apparatus for the conveyor 15 since the jaws 33 and 34 must operate in proper timed relation to the movements thereof and operates against the tension of the spring 44 which is attached to both jaws 33 and 34 and which separates them when the slide 40 again moves down. At the upper limit of movement of the slide 40 the block 35 passes over the upper edge of the block 45 to trim off both leads to the desired length, whereupon a short rest interval occurs in which the grooving or notching portion of the apparatus completes its cycle of operation.

The grooving or notching portion of the apparatus at station A comprises the circular disc-shaped roll 46 which turns freely on the spindle 46' of the arm 47 attached to the slide 48 and which is caused to move across the lower ends of the leads 20 and 21 so that a transverse notch or groove 20' (Fig. 5a) is rolled in one lead 20 and then in the other lead 21. The leads 20 and 21, which are in this particular instance made of nickel, do not move or twist during the grooving operation as they are gripped between the finger 32 and the block 35 and rest against the face of block 35, and no difficulty is experienced making accurately shaped and positioned grooves to one half the thickness of the leads 20 and 21. As in the prior instance, the apparatus is preferably actuated by cam controlled means (not shown) which is connected by rod 49 to the lever 50 pivoted on the pin 51 on the back of the standard 39 which lever 50 engages the pin 52 in a portion of the slide 48 extending through the ways in which said slide 48 is located. The return movement of the roll 46 does not occur until the jaws 33 and 34 are separated and the head 16 is in the course of indexing to the next station. By combining the lead trimming and grooving apparatus in one unit very accurate control is afforded over the portions of the leads 20 and 21 extending

beyond the grooves therein which is an advantage in flash lamps as it causes said flash lamps to be more uniform, a very important feature. The leads 20 and 21 in such lamps become coated by a primer composition during the process of dipping the filament into the primer, and if they are not of uniform length the result is an excess of primer material on the lamp mount.

The indexing movement of the carrier 15 advancing the stem 19 to station B positions said stem 19 at a definite location with respect to the various sections of the mounting apparatus at this station which apparatus grips the leads 20 and 21 of said stem 19 to hold them in place, brings the filament wire 53 into mounting relation thereto, spaces said leads 20 and 21 a pre-determined amount and then squeezes the metal of the leads 20 and 21 over and around portions of the filament wire 53 to permanently attach them together and form an exceptionally good electrical and mechanical connection therebetween. The cycle of operation of this portion of the apparatus begins before the stem 19 is carried to station B in that the filament wire 53 which is to be attached to said stem 19 is withdrawn from the spool 54 while the said stem 19 is in motion. The spool 54, as shown in Figs. 1 and 7, is mounted on a spindle 55 on an outwardly extending arm of the carriage 56 and, in this particular instance holds filament wire 53 of less than .001 inch diameter, a wire of smaller size than usually considered practicable for hand mounting on large scale production schedules. The end of the wire 53 extending from the spool 54 is threaded through the guide tube 57 on the post 58 extending from the carriage 56, between the friction blocks 59 and 60 (Figs. 1, 4 and 7) and through the opening in the guide 61 and extends a definite distance beyond the face of the guide 61.

As the cycle of operation of this apparatus begins, the jaws 62 and 63 are moved from a retracted position to a position where they can close on the end of the wire 53 by a corresponding movement of the slide 64 which carries the pins 65, 66 on which they are mounted. This movement of the jaws 62 and 63 is possible at this time since the carriage 56 which is mounted in slide ways in the standard 67 is located back in said ways out of the path of movement of the carrier head 16 and stem 19. The ways for the slide 64 are defined by the bracket 68, which is attached to the carriage 56, and the movable gib 69 which is forced into engagement with said slide 64 so as to offer a limited amount of resistance to movement thereof by the expansion of the springs 70. The springs 70 butt directly against the gib 69 and the bar 71, the latter of which is mounted on two studs 72 extending upwardly from the bracket 68 through openings in the gib 69 and the open center of the springs 70. The movement of slide 64 is, in turn, produced by movement of the sub-slide 73 located in ways in said slide 64 as the pin 74 in the far end of the said slide 64 is then against the end of the opening 75 in the sub-slide 73, and the movement of said sub-slide 73, which is brought about through arm 76 and the pin 77 extending from the face of the sub-slide 73, is transferred directly thereto. The forward limit of motion of the slide 64 and the sub-slide 73 is determined by the engagement of the stop screw 78 (Figs. 1 and 7) with the bracket 68. Other portions of the operating apparatus for the slide 64 and sub-slide 73 comprise the shaft 79, to which the arm

76 is attached, which extends through a portion of the standard 67; the arm 80 on the opposite end of said shaft 79 which is biased by the spring 81 and which engages the lever 82 through the roller 83; and the lever 82 which is pivoted on the pin 34 carried by the standard 67 and which is operated by cam actuated means of the main portion of the machine through the rod 85.

One function of the jaws 62 and 63 is to pull the end portion of the wire 53 to a position in the apparatus which allows it to be carried into mounting relation to the leads 20 and 21 of the stem 19 at station B by succeeding operations of the apparatus. This function of the jaws 62 and 63 is created through a closing motion which causes them to grip the end of the wire 53, and a retracting movement which causes the wire 53 to be pulled from between the friction blocks 59 and 60 to the desired position. Additional wire 53 is drawn off the spool 54 during this latter interval. Both operations of the jaws 62 and 63 are the result of the returning movement of the arm 76, as the first portion of said movement causes the sub-slide 73 to slide in its ways within the slide 64 until the shank of pin 77 engages the angular inner faces 87 of the jaws 62 and 63, forcing them to close, whereupon all further movement of the arm 76 and pin 77 moves the jaws 62 and 63, the slide 64 and the sub-slide 73 as a unit. At the limit of motion, a taut section of the wire 53 extends between the ends of the jaws 62 and 63 and the friction blocks 59 and 60 because of the resistance offered to movement of the wire 53 thereby. The resistance offered by the friction blocks 59 and 60 results partially from pressure exerted against block 59 by the expansion force of the spring 88 which is located between the arm 89 of the bracket 90 and the head 91 of the pin 92 and occurs as said blocks 59 and 60 are stationary members, block 60 being attached directly to the bracket 90 and block 59 being located in a channel in block 60 and held by the presence of the head 91 of the pin 92 in a depression (not shown) therein. The pin 92 is slidably mounted in the arm 89 of the bracket 90 and can be raised to allow the block 59 to be removed so that the wire 53 can be placed between said friction blocks 59 and 60 when a new spool of wire 53 is inserted into the apparatus. When a new wire 53 is being inserted, the guide 61 which is located adjacent the ends of the friction blocks 59 and 60 is swung upward about the screw 93, which attaches it to the block 60, so that the wire 53 can be threaded through the opening in it more readily. After the threading takes place, the guide 61 is pushed down until the stop screw 94 engages the extension 95 on the block 60 whereupon the guide 61 and wire 53 are correctly positioned and the friction block 59 can be reinserted.

All of the apparatus described immediately above, except for a small portion of the jaw actuating apparatus, is mounted on the carriage 56 which remains stationary in the back portion of the ways in the standard 67 in which it is located. However, now that said apparatus has operated, the said carriage 56 is moved forward to carry the positioned portion of the filament wire 53 into the grooves in the ends of the leads 20 and 21. This movement of the carriage 56 is under the control of the lever 96 which engages the pin 97 in the central opening in the back part of the carriage 56 and is produced by cam actuated means (not shown) engaging said lever 96 through the

rod 98 and the link 99. The lever 96 is pivoted on the pin 100 held by the standard 67.

Before the movement of the carriage 56 causes the filament wire 53 to engage the said leads 20 and 21, said leads are positioned laterally in the apparatus as well as at a definite distance from the carriage 56. The first of these positioning operations is produced by the closing movement of two jaws 101 and 102 (Fig. 4) which close 10 sufficiently to carry the notched plate 103 and block 104 respectively against opposite faces of the very ends of said leads 20 and 21. The angular faces 103' on the end of the plate 103 bordering the notch 104' therein (see Figs. 4 and 15 4a) engage the leads 20 and 21 and draw them toward each other so that they are positioned laterally and are spaced. A very definite length of the filament wire 53 is therefore required to bridge the space between leads 20 and 21 and all 20 filament assemblies constructed by the apparatus are assured of having very uniform characteristics. The second positioning operation occurs when the movement of the carriage 56 causes the extended end of the slide 105, which is located below the plate 106 in ways in said carriage 56, to engage the lower portions of said leads 20 and 21, thereby causing said leads 20 and 21 to be tightly gripped between said slide 105 and the stationary finger 107. As the carriage 56 completes its movement a spring 108, 30 which is located in a well in the end of said slide 105 and butts against the plate 109 held by the carriage 56, is compressed. A pin 110 in the top of the slide 105 engages the end of the slot in the plate 106 and keeps the slide 105 in place when it does not contact the leads 20 and 21. The slide 105 and the stationary finger 107 engage the leads 20 and 21 directly above the 35 grooves therein so as to eliminate any possibility of said leads 20 and 21 being bent during the mounting operation, and they accurately position said leads 20 and 21 since finger 107 is mounted on an arm 111 extending from a stationary part 40 (not shown) of the machine.

45 The limit of motion of the carriage 56 is reached when the taut section of the filament wire 53 is located within the grooves of the leads 20 and 21, as shown in Fig. 5b, and the stop screw 112 on the bracket 113 extending rearwardly of the carriage 56 engages the standard 67. The above apparatus is particularly well suited to the mounting of very short filaments in that very accurate placement of the leads 20 and 21 is provided for, and in that comparatively 50 great working clearance is provided about the filament wire 53 and lead ends as the filament wire presenting apparatus is located on the outer sides of the leads 20 and 21.

The filament wire 53 is fastened to the leads 60 20 and 21 by a further closing movement of the jaws 101 and 102 (Figs. 4 and 8) which now occurs and which causes the raised portion 114 of the block 104 of jaw 102 to be pressed into the grooved area of both leads 20 and 21 so that 65 the metal of said leads 20 and 21 is squeezed from position and flows about the filament wire 53. The block 115 on jaw 101 engages the opposite side of said leads 20 and 21 during the squeezing operation and prevents said leads 20 and 21 from being moved out of position. Each lead end now appears as in Fig. 5b. The jaws 101 and 102, which are both pivotally mounted on the pin 116 extending from the slide 117, are 70 actuated in the above manner by the upward movement of the sub-slide 118 which forces the 75

wedge shaped end thereof to the limit of its movement between the rollers 119 on the lower end of the jaws 101 and 102. The sub-slide 118 is in turn operated by cam actuated means (not shown) which is a part of the mount making machine and which is connected thereto by the rod 120 and link 121.

Although the filament wire 53 is now securely fastened to the leads 20 and 21, said wire 53 is still part of the main body thereof and must be severed therefrom. The severing operation occurs immediately after the filament wire 53 is attached to the leads 20 and 21 and is the function of the circular knives 122 and 123 (Fig. 4) which are located relatively near the lead 20 and which are rotated in opposite directions so as to cause their cutting edges 124 and 125 to engage said wire 53. The knives 122 and 123 rotate about a common center since the former is mounted on a tubular shaft 126 extending through the bracket 90 and the latter is mounted on the shaft 127 located within shaft 126, and are actuated by the particular rotative movements produced in the shafts 126 and 127 by the arms 128-129 and links 130-131 which connect them to the rod 132. The shaft 126 terminates at its left end (Fig. 4) at the arm 128, while the shaft 127 terminates at the arm 129, both shafts being shown broken away at the face of cutter 122 for the sake of clearness. The expansion force of the spring 133 which is located between arms 128 and 129 holds the shafts 126 and 127 so that the adjacent faces of the knives 122 and 123 are in contact with each other at all times. Cam actuated means (not shown), a part of the mount making machine, provides for the movement of the rod 132 by raising the rod 134 (Figs. 6 and 7) so that the shoe 135 engages the roller 136 on the lower end of said rod 132 and raises the said rod 132. A spring 137 located between the larger lower end of the rod 132 and an arm of the bracket 138 which holds said rod 132 in position and which is attached to the under side of the carriage 56 is compressed during the above operation.

The succeeding operations of the apparatus at station B separate said apparatus from the leads 20 and 21 and the section of filament wire 53' mounted thereon and include an opening movement of the jaws 62 and 63, and backward movement of the carriage 56, and opening and downward movements by the positioning and clampings jaws 101 and 102. The jaws 62 and 63 are opened by a movement of the arm 76, pin 77 and sub-slide 73 toward the left (Fig. 4) which movement carries the pin 77 away from the angular faces 87 of the jaws 62 and 63 and the studs 139 into engagement with the angular back portions 140 of said jaws 62 and 63. The arm 76 and sub-slide 73 do not move to such an extent as to change the position of the slide 64 and the jaws 62 and 63 but separate said jaws 62 and 63 so that the carriage 56 can be moved back by motion of the lever 96 until all parts thereon are free of the leads 20 and 21. The positioning and clamping jaws 101 and 102 are opened and lowered by a downward movement of the sub-slide 118 which carries the upper end thereof from between the rollers 119 allowing the contraction of spring 141 to open said jaws 101 and 102 and which brings the shoulder 142 thereon against the plate 143 (as shown in the sectional view of this apparatus in Fig. 9) causing said plate 143, slide 117 and the jaws 101 and 102 to move therewith. At the particular moment the shoulder

142 on the sub-slide 118 engages the plate 143 illustrated in Fig. 9, the slide 117 is held at its upper limit of movement within the ways in the standard 144 by the expansion force of the spring 145 (Fig. 9) which is located in a well in said slide 117 and butts against the piston 146 resting on the projection of the standard 144. The upper position of the slide 117 is determined by the engagement of the portion 147 of the slide 117 extending through an opening in the standard 144 with the stop screw 148 held by said standard 144.

It is often desirable to operate the mounting machine as a whole although no stem or only an incomplete or otherwise defective stem is being presented at station B and there is, therefore, no need for presenting the filament wire 53 at said station. Means, such as that shown in combination with the apparatus at station B, is therefore preferably provided to prevent said apparatus from feeding filament wire 53 although the actuating means for it is operated by the mounting machine as usual. The above means is operated by the solenoid 149 (Fig. 6) which is mounted on the standard 67 and which is under the control of an electrical circuit completed either by a manually operated switch (not shown) or by a movable finger (not shown) located at station A, which finger is caused to close said circuit when a stem is located at said station. The finger can be so located that a defective stem, a stem with only one lead wire, for instance, will not actuate it sufficiently to close the control circuit.

Should the control circuit be open, the expansion force of the spring 150, which is located between the bracket 151 on the standard 67 and the collar 152 on rod 153, will cause said rod 153 to drop to the lower limit of its movement as the armature of the solenoid 149, which is attached to the lower end thereof, will have no effect thereon. The top end of the rod 153 is then below the path of travel of the downwardly projecting end portion 154 of the bar 155 and the bar 155 which is mounted in slide ways in the carriage 56 will be free to move forward in said ways until it is located in the path of movement of the operating arm 76 for the jaws 62 and 63. This movement of the bar 155 does not take place however until the carriage 56 is moved toward the stem 19 in delivering the filament wire 53 to the stem 19 now at station B, as the pawl 156 which is pivoted on the pin 157 extending from the carriage 56 strikes the lug 158 attached to the standard 67 allowing the biasing force of the spring 159 to move the rod 155 to that position. The pawl 156 is at other times biased by the spring 160 so that it is located in the notch 161 in the rod 155 and prevents any movement of said rod 155 with respect to the carriage 56. The rod 155 does not disturb the present cycle of operations of the apparatus while it is located in this position since the arm 76 is still allowed sufficient freedom of movement to open the jaws 62 and 63 after the filament wire 53, it now carries, is attached to the leads 20 and 21 of the stem 19 but is so positioned that it is engaged by the stop screw 162 on said arm 76 and does prevent the movement thereof which causes said jaws 62 and 63 to grip and draw out filament wire 53 in the succeeding cycle of operation. The biasing force of the spring 81 of the operating means for the arm 80 then can not operate said means as directed by the lever 82.

The bar 155 is not, of course, engaged until the

carriage 56 moves back from the stem 19 and remains engaged until the arm 16 and jaws 62 and 63 return to their opposite limit of movement in preparation for the forward movement of the carriage 56. At this time the head 16 of the carrier 15 which was located at station A and which has caused the interruption in the feeding of filament wire 53 will have advanced to station B and a second head 16 and stem 19 will have advanced to station A. If the present stem 19 (at 10 station A) is defective and the control circuit to the solenoid 149 is not closed, the position of the bar 155 will remain the same and no filament wire 53 will be presented at station B in the next succeeding cycle of operation of the apparatus as well as in the present cycle now partly completed. If the stem 19 is such that circuit is closed to the solenoid 149, the armature and the rod 153 will be raised into the path of the downwardly extending end portion 154 of the bar 155 during the 20 forward movement of the carriage 56, and said bar 155 will be drawn back in said carriage 56 so as to be out of the path of movement of arm 16 by said movement. The pawl 156 can then swing up into the notch 161 and hold the bar 155 in the 25 retracted position as the carriage 56 moves back and starts the next cycle of operation. The stem 19 indexed from station B has mounted thereon a length 53' of the filament wire 53 and is in this form commonly referred to as a mount.

The operations of the mounting apparatus are under constant observation, as the mount indexed beyond station B is subjected to a test procedure which includes operations at both stations C and D. The first test operation, which takes place 35 at station C, includes the placing of the filament-to-lead connections under tension in an attempt to separate the filament and the leads. Although this operation tests the mechanical strength of the filament-to-lead connections, it is also effective in discovering defective high resistance connections, as nearly all such connections are loose or of low mechanical strength. The second test operation, which takes place at station D, includes the connection of the leads and filament in an electrical circuit and the testing of said circuit to discover if the mount has the proper electrical resistance and is therefore properly made.

The improperly constructed mounts which are all of higher than normal resistance are discharged from the heads 16 of the carrier 15 and are moved away from the mounting apparatus by a conveyor. Both test operations are dependent to a certain extent on each other, the first operation depending on the discovery and the discharge of partially defective mounts which are rendered entirely defective thereby, and the second operation depending on the discovery of certain defective mounts which could in certain specific instances pass said operation. The first test operation separates the filament from one of the leads when a filament-to-lead connection is insecure and allows the use of less sensitive apparatus for the second test operation if desired, as said apparatus need only discover if the circuit through the mount is complete. The first test operation also discovers certain filament-to-lead connections which have only slightly more than normal resistance and are difficult for the second test apparatus to discover.

The test operation occurring at station C is the result of an outward movement of the finger 163 (Figs. 1 and 10), which carries it between the leads 20 and 21 at a point near the stem 19, and a

5 downward movement thereof, which forces it against the angular portions 164 (Fig. 2) of said leads 20 and 21. The finger 163 is in effect a part of arm 165 as it is pivotally mounted on the pin 166 in the arm which is, in turn, pivotally mounted on the pin 167 held by lever 168 and is actuated through the movements of said lever 168 about the pin 169 held by the standard 170. At the start of the cycle of operation, the arm 165, which is biased by the spring 171 extending between the pin 167 and a post on said arm 165, is positioned with respect to lever 168 by the engagement of the stop screw 172 with the back edge thereof; and the movement of the lever 168 which is operated through the rod 173 by cam actuated means (not shown), a part of the mounting machine, causes a similar movement of the finger 163. The arm 165 remains in this position until the finger 163 is located between the leads 20 and 21 whereupon a portion of it engages the head of the stop pin 174 and the further movement of lever 168 causes the arm 165 to turn about the pin 167 and the finger 163 to swing down against the leads 20 and 21. The stop pin 174 is located within an opening in the sleeve 175 which is attached to the arm 176 extending from the standard 170 and serves as a stationary rest for the arm 165 until the pressure of the finger 163 increases to a predetermined value. 30 After the pressure reaches this point, the stop pin 174 is pushed back in the sleeve 175 and so as to compress the spring 171 and prevent any further increase in pressure on the leads 20 and 21 by permitting the arm 165 to turn about pin 167. The effect of this operation is to pry the leads 20 and 21 apart by pulling a lead from the filament if one of the connections thereto is not tight and secure. The test apparatus is particularly useful as it breaks the circuit from one lead to the other in instances where current can flow satisfactorily through said mount at the time it is manufactured but which will prove unsatisfactory when used. Means are provided for changing the position of the sleeve 175 and the compression of the spring 171 to provide for the adjustment of the pressure exerted by the finger 163. The cycle of operations of this portion of the test apparatus is completed by the reverse movement of lever 168 which lifts finger 163 from the leads 20 and 21 and then swings it to one side of the mount.

40 The test operation taking place at station D starts with a movement of the slide 178 which carries the spring contacts 179-180 (Figs. 1 and 11) into engagement with the leads 20 and 21 and is produced by a corresponding movement of the defective mount conveyor 181 which causes the collar 182 on shaft 183 to butt against and push said slide 178. The slide 178 is normally located out of the path of movement of the mount (that is, to the right of the position in which it is shown in Fig. 1) in the ways in the stationary portion 184 of the machine and, in 45 moving, causes the spring 185 which extends between posts held by said slide 178 and the stationary portion 184 of the machine to be stretched. A slot in the slide 178 prevents the spring post attached to the stationary portion 184 of the machine from interfering with the movements thereof.

50 The movement of the defective stem conveyor 181 is produced through cam actuated means (not shown), a part of the mount making machine, 55 which engages the supporting bracket 186 for

shaft 183 and, in moving said shaft 183, advances one of the holders 187 on the chain 188 engaging the sprocket 189 on the upper end of the shaft 183 to a position below the flange of the stem tube 19 of the mount. The spring contacts 179 and 180, which are insulated from the slide 178, connect the leads 20 and 21 and the filament 53' in a circuit including the coil 190 of the relay 191 which is so proportioned and adjusted that the current conducted through an acceptable mount causes the armature 192 of said relay 191 to be repositioned. If the mount is not acceptable, that is if one of the lead-to-filament connections is imperfect or if the mount is defective in any way effecting its electrical resistance, insufficient current passes through the relay 191 and the position of the armature 192 is not affected.

The relay 191 can be so accurately adjusted as to be actuated by mounts having a lead-to-filament connection of only slightly more than normal resistance but need not be so adjusted in every instance as, ordinarily, the mounts that are defective in this particular have the filament separated entirely from one of the leads 20 and 21 due to the operations of the apparatus at station C. Assuming that the present mount is acceptable, the armature 192 of relay 191 is moved away from the contact 193 so that the electrical circuit controlled thereby is ineffective in causing operation of other portions of the apparatus and the defective mount conveyor 181 completes its cycle of operation by moving back away from the mount which is then indexed from station D. The mount is therefore carried from station D by the regular indexing movements of the head 16 and is removed either manually or automatically from the mount making machine at a succeeding station.

If the mount is not acceptable, another chain of operations occurs before the defective mount conveyor 181 is moved back from station D, which conveyor 181 is moved back from station D, which conveyor 181 and is moved back therewith. This chain of operations is started by the closing of the switch 194 comprised of the stationary and movable contacts 195 and 196 which are connected in a circuit including the armature 192 and contact 193 of the relay 191, the indicator lamp 193' and the solenoids 197 and 198 (see Figs. 1 and 11). The said switch 194 is closed for an interval between each index of the head 16 by cam actuated means (not shown), a portion of the mounting machine. The continuous circuit formed when both relay 191 and switch 194 are closed causes the solenoid 197 to move its armature 199 so that the lever 200, which is located adjacent the upper extremity of the head, engages and turns the jaw release lever 29 (Figs. 2 and 11). This causes the jaws 17-18 and 22-23 to open and release the mount. The continuous circuit also causes solenoid 198 to move the armature 201, thereby turning the lever 202 (Figs. 1 and 11) so that the pin 203 is positioned in the offset portion 204 of the slot 205 in said lever 202. The back movement of the defective mount conveyor 181 occurs before the contacts 195 and 196 are separated and the lever 206 which holds the pin 203 is caused to turn about the shaft 183 so that the pawl 207 turns the ratchet wheel 208 attached to said shaft 183 causing the defective mount conveyor 181 to be indexed. In this way the holder 187 of said conveyor 181 receiving the defective mount is

5 indexed along and the next holder thereof is brought into position to receive a mount. The contacts 195 and 196 are separated before the head 16 is indexed so that the apparatus is again 10 subject to the test circuit established through a mount in the next cycle of operation.

The test apparatus disclosed is particularly effective in the combination shown, in that the filament 53' is very probably of extremely small size, .0006 to .001 inch diameter, for instance, and therefore of low strength, and in that the filament-to-lead connections of the mount manufactured in this instance must have exceptionally good electrical conductive qualities. The test apparatus is also particularly well adapted to test mounts having filament-to-lead connections of the type disclosed.

The test apparatus disclosed herein is claimed in my copending application Serial No. 474,574 filed February 3, 1943 which is a continuation-in-part of the present application.

What I claim as new and desire to secure by Letters Patent of the United States is:

1. In a machine of the character described, the combination of a movable carrier having stem holding heads each constructed and arranged to hold a stem with a pair of metal leads extending therefrom, apparatus located along the path of movement of the heads for making a groove in each of the leads, apparatus farther along said path for placing portions of a filamentary wire in the grooves in the metal leads and thereafter working portions of said metal leads adjacent the grooves over said filamentary wire to securely fasten the said wire thereto.
2. In a machine of the character described, the combination of a movable carrier having stem holding heads each constructed and arranged to hold a stem with a pair of metal leads extending therefrom, apparatus located at a station along the path of movement of the heads for making a groove in each of the leads and for trimming said leads to length at points beyond the grooves, apparatus at another station farther along said path for placing portions of a filamentary wire in the grooves in the metal leads and thereafter working portions of said metal leads adjacent the grooves over said filamentary wire to securely fasten the said wire thereto.
3. In a machine of the character described, the combination of a movable carrier having stem holding heads each constructed and arranged to hold a stem with a pair of metal leads extending therefrom, apparatus located at a station along the path of movement of the heads comprising a pair of blocks having coacting shearing edges, a finger located opposite one of said blocks, means for causing a relative movement between the blocks to trim the leads to length and position one of said blocks against the end portion of the leads and causing said finger to hold said leads against the said block and means engaging the opposite sides of said leads from the said block for making grooves therein, apparatus at another station farther along said path for placing portions of a filamentary wire in the grooves in the metal leads and thereafter working portions of said metal leads adjacent the grooves over said filamentary wire to securely fasten the said wire thereto.
4. In a machine of the character described, the combination of a movable carrier having stem holding heads each constructed and arranged to hold a stem with a pair of metal leads extending therefrom, apparatus located along the path of movement of the heads comprising means for

holding the end portions of said leads in a definite position, a roll having a V-shaped edge, and means for moving said roll transversely of said leads to cause the edge thereof to engage and form a groove in the end portion of each of the leads, apparatus farther along said path for placing portions of a filamentary wire in the grooves in the metal leads and thereafter working portions of said metal leads adjacent the grooves over said filamentary wire to securely fasten the said wire thereto.

5. In a machine of the character described, the combination of a movable carrier having stem holding heads each constructed and arranged to hold a stem with a pair of metal leads extending therefrom, apparatus located at a station along the path of movement of the heads comprising a pair of blocks having coacting shearing edges, a finger located opposite one of said blocks, means for causing a relative movement between the blocks to trim the leads to length and position one of said blocks against the end portion of the leads and causing said finger to hold said leads against the said block, a roll having a V-shaped edge and means for moving said roll transversely of said leads to cause the edge thereof to engage and form a groove in the side of each lead opposite from the said block, apparatus at another station farther along said path for placing portions of a filamentary wire in the grooves in the metal leads and thereafter working portions of said metal leads adjacent the grooves over said filamentary wire to securely fasten the said wire thereto.

6. In a machine of the character described, the combination of a movable carrier having stem holding heads each constructed and arranged to hold a stem with a pair of metal leads extending therefrom, apparatus located along the path of movement of the heads for making a groove in each of the leads, apparatus farther along said path comprising means for holding spaced portions of a filamentary wire, a carriage for supporting said means adapted to move the said means to and from operative relation to the head, means for moving the carriage to cause the filamentary wire to be placed in the grooves in the leads and means for working portions of the metal leads adjacent the grooves over the filamentary wire to securely fasten said wire thereto.

7. In a machine of the character described, the combination of a movable carrier having stem holding heads each constructed and arranged to hold a stem with a pair of metal leads extending therefrom, apparatus located along the path of movement of the heads for making a groove in each of the leads, apparatus farther along said path comprising a carriage adapted to move to and from operative relation to the head, means mounted on said carriage for holding a filamentary wire, movable jaws mounted adjacent said last mentioned means on said carriage, means for causing said jaws to grip a portion of the filamentary wire extending beyond the holding means and for moving said jaws away from said holding means to draw a portion of the filamentary wire therefrom, means for moving the carriage to cause the filamentary wire to be placed in the grooves in the leads, and means for working portions of the metal leads adjacent the grooves over the filamentary wire to securely fasten said wire thereto.

8. In a machine of the character described, the combination of a movable carrier having stem holding heads each constructed and arranged to hold a stem with a pair of metal leads extending

therefrom, apparatus located along the path of movement of the heads for making a groove in each of the leads, apparatus farther along said path comprising a carriage adapted to move to and from operative relation to the head, means mounted on said carriage for holding a filamentary wire, a slide mounted in ways in the carriage adjacent said last mentioned means, jaws mounted on said slide, a sub-slide mounted in ways in said slide, means engaging the slide and sub-slide for limiting the movements of the latter with respect to the former, means engaging the sub-slide and the jaws for causing said jaws to close or open at the limits of the motion of the said sub-slide, means for moving the sub-slide in one direction to cause the jaws to grip a portion of the filamentary wire extending beyond the holding means and movement of the slide and jaws to draw a portion of the filamentary wire therefrom and for moving the sub-slide at a later interval for opening the jaws and returning said sub-slide and slide to their original position, means for moving the carriage to cause the filamentary wire to be placed in the grooves in the leads, and means for working portions of the metal leads adjacent the grooves over the filamentary wire to securely fasten said wire thereto.

9. In a machine of the character described, the combination of a movable carrier having stem holding heads each constructed and arranged to hold a stem with a pair of metal leads extending therefrom, apparatus located along the path of movement of the heads for making a groove in each of the leads, apparatus farther along said path comprising a carriage adapted to move to and from operative relation to the head, means mounted on said carriage for holding a filamentary wire, movable jaws mounted adjacent said last mentioned means on said carriage, means for causing said jaws to grip a portion of the filamentary wire extending beyond the holding means and for moving said jaws away from said holding means to draw a portion of the filamentary wire therefrom, means for moving the carriage to cause the filamentary wire to be placed in the grooves in the leads, means for working portions of the metal leads adjacent the grooves over the filamentary wire to securely fasten said wire thereto, and independently operable means for preventing the full return movement of the jaws to prevent said jaws from gripping and positioning the filamentary wire in the succeeding cycle of operation.

10. In a machine of the character described, the combination with a movable carrier having stem holding heads thereon each constructed and arranged to hold a stem with a pair of spaced leads extending therefrom, of filament mounting apparatus comprising a carriage member located adjacent the path of travel of said heads, means on said carriage for holding a supply of filament wire, gripping means on said carriage for holding taut an end portion of said filament wire, and means for bodily moving said carriage toward one of said heads to carry the taut end portion of filament wire directly against and across the leads of a stem in said head.

11. In a machine of the character described, the combination with a movable carrier having stem holding heads thereon each constructed and arranged to hold a stem with a pair of spaced leads extending therefrom, of filament mounting apparatus comprising a carriage member located adjacent the path of travel of said heads, means on said carriage for holding

a supply of filament wire, gripping means on said carriage for holding taut an end portion of said filament wire, jaw members adjacent said carriage, means for bodily moving said carriage toward one of said heads to carry the taut end portion of filament wire directly against and across the leads of a stem in said head, and means for subsequently closing said jaw members against said leads to secure the filament thereto.

12. In a machine of the character described, the combination with a movable carrier having stem holding heads thereon each constructed and arranged to hold a stem with a pair of spaced leads extending therefrom, of filament mounting apparatus comprising a carriage member located adjacent the path of travel of said heads, means on said carriage for holding a supply of filament wire, gripping means on said carriage for holding taut an end portion of said filament wire, jaw members adjacent said carriage, knife means on said carriage, means for bodily moving said carriage toward one of said heads to carry the taut end portion of filament wire directly against and across the leads of a stem in said head, and means for subsequently actuating said knife means to sever the secured taut end portion of the filament wire from the remainder thereof.

13. In a machine of the character described, the combination with a movable carrier having stem holding heads thereon each constructed and arranged to hold a stem with a pair of spaced leads extending therefrom, of filament mounting apparatus comprising a carriage member located adjacent the path of travel of said heads, means on said carriage for holding a supply of filament wire, gripping means on said carriage for holding taut an end portion of said filament wire, jaw members adjacent said carriage, the said gripping means being spaced sufficiently far apart that the free portion of taut wire therebetween is longer than the spacing of the leads, means for bodily moving said carriage toward one of said heads to carry the taut end portion of filament wire directly against and across the leads of a stem in said head, and means for subsequently closing said jaw members against said leads to secure the filament thereto.

14. In a machine of the character described, the combination with a movable carrier having stem holding heads thereon each constructed and arranged to hold a stem with a pair of leads depending vertically therefrom, of filament mounting apparatus comprising a carriage located adjacent the path of travel of said heads, means on said carriage for holding a spool of filament wire, clamping means on said carriage arranged to resiliently clamp a part of said wire with an end portion projecting therebeyond, a pair of movable jaws spaced horizontally from said clamping means a distance greater than the spacing of the said leads, means for moving said jaws toward said clamping means to grip said end portion of said wire and for then retracting said jaws to pull a portion of the wire through the clamping means and hold it taut in a horizontal position, and means for bodily moving said carriage toward one of said heads to carry the taut portion of filament wire directly against and across the leads of a stem in said head.
15. In a device of the character described, mechanism for grooving a pair of vertically extending leads of a stem, comprising a pair of vertically disposed jaws, a positioning finger at the upper end of one of said jaws extending laterally toward the other jaw and having notches in its front edge adapted to engage the said leads and space them a definite distance apart, a block member on said one jaw under said positioning finger providing a vertical face for backing portions of said leads, a holding finger on said other jaw extending laterally toward said one jaw and arranged to clamp said leads securely against the said face of said block member adjacent the lower edge of said face, a second block member carried by said other jaw under said holding finger and arranged to pass across tip portions of said leads projecting below the first-mentioned block member, the said block members constituting shear means for severing the said tip portions of the leads, and a disc-shaped roll member having a sharp periphery arranged to be pressed against portions of said leads backed by said first-mentioned block member above said holding finger to form horizontal grooves in said leads.

JOHN FLAWS, JR.
